UNITED STATES PATENT OFFICE.

JACKSON D. COMSTOCK AND IRVIN E. FAIR, OF CHESTER, WEST VIRGINIA.

DESIGN FOR A TIRE TREAD.

Application filed October 20, 1921. Serial No. 509,186. Term of patent 14 years.

To all whom it may concern:

Be it known that we, JACKSON D. COMSTOCK and IRVIN E. FAIR, citizens of the United States, residing at Chester, in the county of Hancock and State of West Virginia, have invented a new, original, and ornamental Design for Tire Treads, of which the following is a specification, reference being had to the accompanying drawing, forming a part thereof.

The drawing is a sectional perspective of our tire tread.

We claim:

The ornamental design for a tire tread, substantially as shown.

JACKSON D. COMSTOCK.
IRVIN E. FAIR.
